UNITED STATES PATENT OFFICE.

ADOLPH L. DE LEEUW, OF CINCINNATI, OHIO, ASSIGNOR TO THE CINCINNATI MILLING MACHINE COMPANY, OF OAKLEY, CINCINNATI, OHIO, A CORPORATION OF OHIO.

OVER-ARM.

1,147,615.

Specification of Letters Patent. Patented July 20, 1915.

Application filed May 10, 1913. Serial No. 766,905.

To all whom it may concern:

Be it known that I, ADOLPH L. DE LEEUW, a citizen of the United States, and residing at Cincinnati, in the county of 5 Hamilton and State of Ohio, have invented a new and Improved Over-Arm, of which the following specification is a full disclosure.

This invention relates to a milling-machine and deals with an improved "over-arm" structure therefor. It is primarily concerned with attaining a structure at once simple, rigid in all directions, inexpensive, and capable of being readily manufactured 10 by regular shop methods so as to conform to the highest standards of precision.

Milling machines as conventionally constructed have provided means for supporting the outer end of the arbor on which the 15 cutter is mounted and adapted to be adjusted into various positions, such supporting means being technically termed an "out-bearing hanger" and ordinarily this merely consists of a sort of bracket having a split 20 clamp-collar circumscribing the "over-arm" which is cylindrical in form and of uniform diameter throughout. Under modern 25 conditions of high duty shop practice, considerable strains are imposed on the 30 "over-arm" and the "out-bearing hanger" by reason of the severe duty of the cutting tool, and these are ordinarily resisted only by the friction provided by the split-collar 35 on the cylindrical over-arm. Furthermore, the shape of the over-arm itself is ill adapted 40 to resist the flexing strains of the cutting tool. Now this invention contemplates a structure effective to overcome those difficulties and in other respects to be better 45 adapted to meet the conditions obtained in modern shop practice.

Other objects will be in part obvious from the annexed drawings and in part indicated in connection therewith by the following 50 analysis of this invention.

This invention accordingly consists in the features of construction, combinations of parts, and arrangements of elements deducible herefrom, and in the relative proportioning and unique disposition and relations of the members thereof; all as more completely outlined herein.

To enable others skilled in the art so fully

to comprehend the characteristics hereof that they may embody the same by the numerous modifications in structural details contemplated by this invention, drawings depicting a preferred form have been annexed as a part of this disclosure, and in such drawings, like characters of reference 60 denote corresponding parts throughout all the views, of which:

Figure 1 is a side elevation of the upper portion of a milling machine embodying this invention, showing the upper end of the 65 column, and the proposed over-arm construction therefor. Fig. 2 is an end elevation, partly in section, showing further details of the same. Fig. 3 is a section taken through line 3—3 of Fig. 1 showing further details in the construction of said parts. 70

Continuing now by way of a more detailed description it may be noted that the over-arm proposed by this invention, instead of being a mere cylindrical piece of stock is 75 of an entirely different description, being preferably in the nature of a hollow shell-like truss.

The column or standard of the machine is indicated by A, and may be similar to conventional design except in respect to the construction of its upper portion, which differs therefrom by dispensing with the usual horizontal cylindrical bore employed for receiving the usual cylindrical over-arm, 85 and in lieu of the usual mounted upper end of the column an over-arm supporting deck or dove-tailed top-face is provided. Thus, the upper extremity of the column A is machined off to form a flat table or top-face 1, 90 which constitutes the deck, upon which rests the over-arm B. This deck 1 is machined accurately parallel with the axis of the bore 2 of the column, which receives the spindle, and the deck 1 is contoured to provide means instrumental in clamping the over-arm B against movement, and to that end it may be provided with a dove-tailed slide way 3, shown by Fig. 3 preferably arranged in symmetrical relation with its middle line. To enable the parts to be clamped together without in any manner impairing the accuracy of the alinement of the parts, two pairs of saw-cuts 4, 5 are preferably made in one side of the column A so as to 105 form integral tongues 6 and 7, which pro-

vide sufficient spring to meet the very slight movement required to secure a very positive clamping action. This movement may be accomplished by means of bolts 8 passing through the column as indicated by Fig. 3, and prevented from turning as by means of the pins 9. A nut 10 on a protruded end of each bolt enables the attendant to draw the tongues into clamping relation with a dove-tail provided by the over-arm.

10 The over-arm B proposed by this invention is in the nature of a truss and preferably consists of a one-piece cast metal shell having its sides 11 forming continuations of 15 the sides of the column. At a suitable point, say approximately midway of the over-hanging portion of this arm B a rib 12 may be cast to stiffen the same and another rib, such as indicated by 13 may be provided in 20 intermediate the supported end of the over-arm and the aforesaid rib. Slanting upwardly from the over-hanging end of the over-arm B toward the point over the column A is a top-face 14 and a similar shorter 25 slanting top-face 15 may also be employed. A suitably placed opening 16 provides for the removal of the core after the casting operation. The under-face 17 of the truss-like over-arm B is machined very accurately 30 in a flat plane and an accurately machined dove-tail exactly interfitting the dove-tailed slide way of the column A is also provided. This enables the over-arm B to be secured in a very accurate relation with the spindle 35 axis of the column A.

The out-bearing hanger C is of a triangular shape and has a wide face or top-deck 19 as well as a dove-tailed slide way 20, which are exact counter-parts of that provided by 40 the column A. This enables the out-bearing hanger C to be adjusted in a straight line along the over-arm B, and it may be clamped rigidly at any station by means of the draw bolt 21 and nut 22, which brings the tongue 45 23 (formed by the saw-slot 24) into clamping relation with the dove-tail 18. In accurate coaxial relation with the spindle an aperture 25 will be provided in the hanger C to receive the end of the arbor mounting 50 the cutter. This hanger C is preferably made of cast metal and in shell like form, as shown by the drawings, so as to provide the maximum rigidity with the greatest strength.

55 It will thus be perceived that this invention achieves an improvement in the structure of a milling machine enabling the end of the arbor to be supported very accurately in coaxial relation with the spindle and at the same time rigidly and by means of a 60 structure well adapted for economic manufacturing.

Without further elaboration, the foregoing will so fully reveal the gist of this invention that others can by applying current 65 knowledge readily adapt it for various ap-

plications without omitting certain features that, from the standpoint of the prior art, fairly constitute essential characteristics of the generic or specific aspects of this invention, and therefore such adaptations should 70 and are intended to be comprehended within the meaning and range of equivalency of the following claims.

Having thus revealed my invention, I desire to claim as new and secure by Letters 75 Patent of the United States:—

1. A milling machine structure of the nature disclosed combining a column, an over-arm comprising a dove-tail slide, an out-bearing hanger interfitting with said slide 80 and comprising a resilient dove-tail slide way, and means adapted to compress said resilient slide way to clamp said hanger against movement on said slide.

2. In a milling machine, an overhanging 25 arm having parallel lower edges of acute angular cross section, an arbor bearing having a pair of V-shaped guideways fitting upon the lower edges of the overhanging arm, one of said guideways being movable 90 toward the other, and a clamping screw for moving said guideway to clamp the arbor bearing in its adjustments on the overhanging arm.

3. In a milling machine, a column having 95 its upper end cut away to form V-shaped guideways with a slot therebetween permitting one guideway to be movable toward the other, a clamping screw for moving said movable guideway, and an overhanging arm 100 having its lower edges angular in cross section and fitting within the V-shaped guideway of the column and clamped therein by the action of the clamping screw.

4. A milling-machine combining a column 105 having its upper end terminating in a horizontally extending dovetail slide-way, said column being locally slotted to form at one side thereof a plurality of resilient slide-way portions integral with said column but 110 spaced apart from one another; an over-arm having its under-portion formed with a complementary dove-tail slide; and clamping screws passing horizontally through said resilient portions and engaging rigid portions 115 of said column, whereby upon tightening said screws said resilient portions will be flexed against the over-arm to bind it against movement.

5. A milling-machine combining a column 120 having its upper end terminating in a horizontally extending dovetail slideway; a hollow truss-shaped overarm having its under portion formed with a complementary dove-tail slide, said overarm being internally provided with bracing ribs; and means for clamping the overarm to the column.

6. A milling-machine combining a column having its upper end terminating in a horizontally extending dove-tail slideway; a 130

truss-like overarm having its under portion formed with a complementary dove-tail slide, and having its upper portion integrally provided with reinforcing ribs; and
5 means for clamping said overarm into this slideway.

In witness whereof, I hereunto subscribe

my name, as attested by the two subscribing witnesses.

ADOLPH L. DE LEEUW.
